UNITED STATES PATENT OFFICE.

MORRIS S. WRIGHT, OF WORCESTER, MASSACHUSETTS, ASSIGNOR TO M. S. WRIGHT COMPANY, OF WORCESTER, MASSACHUSETTS, A CORPORATION OF MASSACHUSETTS.

VACUUM-CLEANER.

1,141,597.

Specification of Letters Patent.

Patented June 1, 1915.

Application filed March 12, 1913. Serial No. 753,757.

To all whom it may concern:

Be it known that I, MORRIS S. WRIGHT, a citizen of the United States, residing at Worcester, in the county of Worcester and State of Massachusetts, have invented certain new and useful Improvements in Vacuum-Cleaners, of which the following is a specification, reference being had therein to the accompanying drawing.

10 This invention relates to improvements in vacuum cleaners and has more particular reference to machines of a portable character, adapted to move over a carpet or other surface, and in its movement to create a vacuum and draw into the machine, through a suitable nozzle, which engages the surface dust and other material from said surface.

Among the aims and objects of the invention may be recited, the provision of a machine of the character mentioned with a view to compactness, and in which the number of parts are few, the construction simple, the cost of production small, and efficiency and operation high.

25 The invention includes a novel construction and relative arrangement of bellows, and dust receiving chamber, and an associated novel construction and arrangement of dust inlet member.

30 Still further, the invention embraces improved means whereby access to the interior of the dust chamber may be readily accomplished, and the collected dust removed, and in this connection includes a dust inlet nozzle and dust receptacle removable together from the machine and novel means for supporting said parts in operative position on the machine.

Another important feature includes in a 40 machine of the character stated a removable dust box, and a removable end wall for the dust box, together with an inlet nozzle, the said end wall being removable independently of the nozzle, to the end that the dust inlet nozzle is maintained in an accurate position relative to the surface and to the dust receptacle, and in air-tight engagement with the latter.

Other and further improvements and 50 novel details in the construction and arrangement of parts will be appreciated from the description to follow, which for a clear

understanding of the invention should be considered in connection with the accompanying drawings, which form a part hereof and wherein preferred embodiments of the invention are shown for the purpose of illustration.

In the drawings, Figure 1 is a side elevation of the machine, the handle being broken away, Fig. 2 is a longitudinal vertical section, parts being shown in elevation, Fig. 3 is a front elevation, Fig. 4 is a transverse vertical section, and Fig. 5 is a longitudinal section of a slightly different embodiment of the invention.

With more particular reference to the drawings, wherein like reference numerals refer to corresponding parts throughout the several views, a casing generally indicated by the numeral 1 is provided, the said casing preferably having relatively fixed top side and end walls, and a bottom wall 2 which preferably inclines from a point adjacent the lower end of the rear end wall upwardly toward the top of the front end wall of the casing. This arrangement affords a convenient support for the bellows, and makes possible a low down construction capable of getting under chairs, beds and other confined places, and the bottom wall 2 is preferably cut out intermediate its sides and adjacent the rear end wall as at 3 for the reception of a supporting roller 4, which latter has a shaft 5 supported in suitable bearings 6 on the wall 2. The said wheel 4 also preferably has a rubber or other friction tread 7. The vacuum creating means preferably comprises a pair of oppositely acting bellows 8, the bottom wall 9 of each of

which is positioned on the upper surface of the inclined bottom 2, and the top wall 10 of which is pivotally connected at its forward end to the forward end of the bottom 9, the enlarged space adjacent the rear end of the casing afforded by the inclined bottom permitting of the necessary expansion of the bellows, and making possible the low down or compact structure desired. The shaft 4 has oppositely projecting crank extensions 11 to which are connected vertically projecting pitman rods 12 which latter are pivotally connected as at 13 to supporting arms or brackets 14 secured in any desired man-

ner to the top wall 10 of the bellows. Because of the relative arrangement of the connections between the respective bellows and the crank shaft, it will be appreciated, 5 that according to the movement of the machine, and the rotation of the wheel 4, said bellows are constantly acting, one being collapsed while the other is expanded. The top wall of the bellows has a suitable air outlet, 10 which is controlled in any desired manner by a spring held valve 15 of any approved construction. The bottom wall 2 of the casing has suitable air inlet openings 16, one for each bellows communicating with an 15 opening in the bellows, the said latter opening being valve controlled as usual, and secured to the bottom surface of the wall 2 is a plate 17 secured at its edges to said bottom wall, and spaced from the bottom wall 20 at points between said edges. A peripheral packing 18 interposed between the edges of the plate 17 and the bottom wall 2 make an air-tight connection between said parts. The said plate 17 overlies the openings 16 in 25 the bottom wall 2 and has an opening 19 adapted to establish communication between the air chamber afforded by said plate 19 and bottom wall 2 and the dust chamber about to be described.

30 The dust chamber is preferably in the form of a dust box of a design and construction to fit in the space of the casing below the bottom wall 2, and preferably comprises a top wall 20, a bottom wall 21, which said 35 walls converge toward their rear ends, and side walls 22. Said walls are preferably relatively fixed, and provide a dust chamber the forward portion of which is enlarged, since it is positioned in the enlarged 40 space adjacent the forward end of the casing below the inclined wall 2, and when so positioned the bottom wall 21 of the dust box will lie in a substantially horizontal plane and has an inlet opening adjacent the front 45 end thereof, as indicated at 23. Secured to the bottom wall 21 adjacent the forward end thereof is a dust inlet nozzle 24 which has an elongated slot 25 communicating with the slot 23 in said bottom wall 21. The nozzle 50 may have and preferably does have a metallic reinforce or facing 26, and said nozzle preferably extends from side to side of the machine and constitutes the support for the forward end thereof. The top wall 20 55 of the dust box has an opening 27 adapted to register with the opening 19 in the plate 17 and positioned on said top wall 20 is a suitable packing 28 surrounding the opening 27 whereby when the dust box is positioned, 60 the same will be in air-tight engagement with the bottom wall 2 of the casing. A dust filtering member 29 is preferably secured to the inside of the top wall 20, as by spacing blocks 30, the filtering member being of any 65 suitable fabric, and a wire fabric 31 inter-

posed between said filtering member and the wall 20 and secured to the latter separates the filtering member from said wall 20 and prevents any portion of the same being sucked up or into the opening under the 70 action of the vacuum creating means, positioned on the wall 2. The top wall 20 has an extension 32 adapted to rest upon one or more spring supports 33 secured upon the bottom wall 3 of the casing. 75

The means for securing the dust box in position on the casing preferably takes the form of a substantially U-shaped bail member 34, the arms 35 of which have offset terminals 36 pivotally mounted in suitable 80 bearings 37 in the bottom 21 of the dust box, the bail being of a size to swing over the front of the casing into a position overlying the top of the casing and adapted to engage suitable spring members 37^a secured at one 85 end to the front wall of the casing and having an opposite free end. It will be appreciated that when the dust receptacle is positioned on the casing with the extension 32 thereof in engagement with the spring supports 33, the bail 34 by being swung into engagement with the free end of the spring arms 37^a will force the dust box into air-tight engagement with the bottom wall 3 90 of the casing. A suitable stop 38 at one 95 or both sides of the casing limits the swinging movement of said bail. A front end wall 39 having a suitable packing 40 is preferably removable independently of the nozzle or other parts of the dust box, the same being preferably supported by the dowel pins 41 on one of the parts comprising said end wall 39 and the side walls 22, and co-operating recesses on the other of said parts. Suitable bow springs 42 positioned on the front 100 surface of said end wall 39 are adapted in the positioning of the dust box to engage the inner surface of the front wall of the casing and maintain an air-tight contact between said removable end wall 39 and the other walls of the dust box through the medium of the interposed packing 40. 105

In the preferred construction, I preferably employ a filtering bag 43 which said bag has a surrounding collar 44 adapted to abut against the collar 45 on the inner surface of the wall of the dust box adjacent the forward end thereof. In this instance, the removable end wall 39 of the dust box 110 has one or more projections 46 adapted to engage one or more bow springs 47 on the filtering bag collar 44. In this way, as the dust box is positioned, the end wall 39 will be brought into air-tight engagement with the co-operating walls of the dust box in the 115 manner previously described, and the projections 46 being brought into contact with the spring members 47 will force the collar 44 of the dust bag into engagement with the abutment collar 45 and in this way sup-

120

125

130

135

port the bag in position. If desired, when the removable bag is employed, the strip of fabric or other filter member 29 previously referred to may, if preferred, be dispensed with.

- 5 In the illustration of the invention disclosed in Fig. 2, wherein the dust bag is dispensed with, it is desirable to provide a suitable deflector 48 acting to guide the dust laden air upwardly toward the opening 31, and this member 48 also serves the additional function of preventing the dust as taken into the dust box from falling out through the opening 23 onto the surface.
- 10 15 A suitable push handle 49 is provided, the same having a bifurcated lower end 50, the arms of which are pivotally connected as at 51, one to each side of the casing.

The operation may be reviewed as follows: The operator imparts back and forth movement to the machine through the medium of the handle, the wheel 4 constituting a support for the rear end of the machine, and the nozzle 24, a support for the forward 25 end of the machine. The movement of the wheel 4 over the surface imparts movement to the respective bellows in opposite directions, whereby the dust or the like will be drawn through the nozzle opening into the 30 dust box, the air being filtered by the bag 43 and by the filtering fabric 29. When desired to deposit the collected dust, the operator swings the bail 34 out of engagement with the springs 37, which operation releases 35 the forward end of the dust box, and the latter may then be readily removed by drawing the forward end of the dust box downwardly, thereby releasing the rear end thereof from the spring supports 33. When removed from the machine, the dust box forms a substantially closed receptacle for the dust, which may be conveniently moved to a place of deposit, when the removable end wall 39 is taken off, thereby permitting of access to 40 45 the interior of the dust box. In case no filtering bag is employed, the dust box is turned upside down and tilted so that the same readily falls off of the surface formed by the filtering member 29 out through the 50 open end of the dust box. When the filtering bag 43 is employed, upon removal of the end wall 39, the operator engages the collar 44 of the bag thereby bodily removing the bag, for emptying purposes.

55 I claim:

1. A portable vacuum cleaner comprising an elongated horizontally disposed casing having a closed front end wall, a supporting wheel, a push handle, vacuum creating means within the casing operatively connected with the supporting wheel, a dust chamber, a filtering bag within the dust chamber, and in communication with the vacuum creating means, a dust inlet nozzle projecting downwardly below said end wall to engage a sur-

face and in communication with the filtering bag, a closure wall inclosing the end of the dust box, said closure wall being inclosed by the casing, and means whereby said closure wall may be bodily removed from the dust 70 box independently of the nozzle.

2. In a vacuum cleaner, the combination of a casing, vacuum creating means, a dust box positioned below the vacuum creating means and inclosed by the side walls of the 75 casing, and having a dust inlet nozzle secured thereto adjacent one end to engage the surface, said dust box and nozzle being removable together as a unit from the casing.

3. In a vacuum cleaner, the combination 80 of a casing having an inclined bottom wall, vacuum creating means positioned on said wall and within the casing, a dust box positioned beneath said wall in communication with said vacuum creating means, said dust 85 box being inclosed by the walls of the casing and having a downwardly projecting inlet nozzle adjacent the forward end thereof.

4. In a vacuum cleaner, the combination of a casing, an elongated partition wall within 90 the casing, vacuum creating means positioned on said wall within the casing, a dust box arranged below said wall and in communication with the vacuum creating means, said dust box having a downwardly 95 projecting inlet nozzle secured thereto, and means for removably supporting the dust box in position against said partition wall and within the casing, and an end wall of the box being also removable. 100

5. In a vacuum cleaner, the combination of a dust box with top, bottom and sides, and a removable end wall, an inclosing casing for said box, a supporting wheel for the casing, vacuum creating means operatively 105 connected with said wheel, and a nozzle adjacent the forward end of the dust box removable therewith and independent of said removable end wall.

6. In a vacuum cleaner, the combination 110 of a casing, having a detachable dust box positioned within the casing and provided with top, bottom and sides, and a removable end wall having retaining means to engage the inner surface of the casing, a supporting 115 wheel for the casing, vacuum creating means operatively connected with said wheel, a nozzle adjacent the forward end of the dust box and independent of said removable end wall, filtering means positioned in said box, said 120 means being removable and adapted to be held in position by said removable end wall of the dust box.

7. In a vacuum cleaner, the combination 125 of a horizontally disposed substantially rectangular casing having intermediate the top and bottom thereof, an elongated supporting member, vacuum creating means positioned on said member within the casing, a bodily detachable dust box arranged below said 130

supporting member and in communication with the vacuum creating means through an opening in said supporting member, a dust inlet nozzle, a bracket adapted to support the rear end of said box, and a yieldable connection between the forward end of said box and the casing.

8. In a vacuum cleaner, the combination of a casing having an elongated supporting member, vacuum creating means positioned on said member, a bodily removable dust box arranged below said supporting member and in communication with the vacuum creating means through an opening in said supporting member, a dust inlet nozzle, a removable front end wall for the box, and a spring interposed between said front end wall and the front end wall of the casing.

9. In a vacuum cleaner, the combination of a casing, a push handle, a supporting wheel, an elongated supporting member in the casing, vacuum creating means on said supporting member having an operative drive connection with the supporting wheel, a dust box positioned below said supporting member, the bottom wall of the dust box having a nozzle inlet opening, the front wall of the casing overlying the front wall of the dust box, a spring on the casing adjacent said front wall, and a pivoted bail on the dust box adapted to engage said spring to support the dust box in position.

10. In a vacuum cleaner, the combination of a casing having a dust box with top, bottom and sides, and an end wall, a supporting wheel for the casing, vacuum creating means operatively connected with said wheel, and a nozzle secured to and projecting downwardly from the bottom wall of the dust box adjacent the forward end of the dust box the end wall of the dust box being detach-

able from the dust box independently of the nozzle.

11. In a portable vacuum cleaner, the combination of a horizontally disposed casing, an elongated partition dividing the casing into an upper and a lower chamber, a wheel support for the rear end of the casing, vacuum creating means operatively connected with the wheel support and positioned in the upper chamber of the casing, a dust receptacle positioned in the lower chamber of the casing, a dust inlet nozzle to engage the surface communicating with the dust box, a forwardly extending support adapted to engage under a part at the rear end of the dust box to form a support for this end of the dust box and a releasable holding member at the front end of the dust box engaging the casing.

12. In a portable vacuum cleaner, the combination of a horizontally disposed dust box, a horizontally disposed vacuum creating means supported upon and in communication with the dust box, a nozzle at the front end of the dust box having a dust inlet opening at its lowest edge communicating with the interior of the dust box, said nozzle being fixed in position relative to the dust box, and said dust box having an elongated transversely extending opening through the front through which the collected dust is removed, a removable closure wall for said opening, and a wheel support for the rear end of the device.

In testimony whereof I affix my signature in presence of two witnesses.

MORRIS S. WRIGHT.
